Primary Examiner—A. Hugo Word*Assistant Examiner*—Eric Watterson[57] **CLAIM**

The ornamental design of a sealing cap, as shown and described.

DESCRIPTION

FIG. 1 is a perspective view taken from the top, front and right side of my sealing cap showing the design in an open position;

FIG. 2 is a bottom plan view of my sealing cap in a closed position;

FIG. 3 is a front elevation view thereof;

FIG. 4 is a rear elevation view thereof;

FIG. 5 is a top plan view thereof;

FIG. 6 is a side elevational view thereof, the opposite side being a mirror thereof; and,

FIG. 7 is a side elevational view, partially cutaway, in a open position.

FIG. 1

FIG. 2
